UNITED STATES PATENT OFFICE.

EDWARD OTT, OF JOHNSTOWN, PENNSYLVANIA, ASSIGNOR TO THE LORAIN STEEL COMPANY, OF PENNSYLVANIA.

RAILWAY-TRACK STRUCTURE.

SPECIFICATION forming part of Letters Patent No. 633,728, dated September 26, 1899.

Application filed July 22, 1899. Serial No. 724,856. (No model.)

To all whom it may concern:

Be it known that I, EDWARD OTT, of Johnstown, in the county of Cambria and State of Pennsylvania, have invented a new and useful Improvement in Railway-Track Structures, of which the following is a full, clear, and exact description, reference being had to the accompanying drawings, which form a part of this specification.

10 This invention relates to railway-track work and more particularly to slot-rail-crossing structures of that class wherein are employed removable hardened wear or center plates.

15 The object of the invention is to provide means of novel character in a structure of this class for securing in place against vertical and lateral displacement the removable wear-plates. Inasmuch as the seats for said plates in structures of this kind are open or partially open at one side, where the wear-plate comes to alignment with and forms a part of the slot-rail face of the structure, which alignment must be insured, it is desirable to provide means of simple and practical character whereby said plate may be securely gripped and secured at its base portion. I accomplish this result by the means now to be described, and hereinafter pointed out in the appended claims, reference being had to the accompanying drawings, in which—

20 Figure 1 is a perspective view of a track or crossing structure embodying the invention, and Fig. 2 is a transverse section thereof on the line X X of Fig. 1.

25 In the drawings the letter A designates a slot-rail member or casting shown as of general L shape in cross-section, with a broad lateral extension a, pocketed or recessed in its upper face to form a seat for the wear-plate B. This recess at its upper portion extends through to the slot-rail face of the casting; but in the shelf or extension a it is deepened to seat a bottom extension B' of the said plate. The inner wall a' of the deepened portion of this recess is under cut or under-beveled, as indicated, and the contiguous face of the extension B' has a corresponding incline or bevel, so that when said plate is seated and forced laterally toward the said wall there is obtained a secure gripping or

locking engagement between the parts, as will be readily seen. I usually provide the wall a' at intervals with projections a² for the purpose of providing for the proper fit of 55 the wear-plate, as these projections may be ground or cut away to suit variations in the plates. The section Fig. 2 is taken through one of these projections, the true line of the wall a, being indicated by the dotted line. I 60 also prefer to provide the bottom of the recess at the base of the wall a' with a longitudinal depression or channel a³, the extension B' having a corresponding rib or swell b, this provision being for the purpose of increasing 65 the engaging or gripping area of the parts. The opposite wall a⁴ of the recess is formed with an overhanging lip a⁵, recessed at a⁶ to provide ways for the insertion of keys C, but one of which is shown. These keys are inserted in said ways and are driven endwise underneath the said lip and between the same and a rib b', formed on the plate B. 70

D indicates spelter or like material, which is poured underneath and around the plate B 75 and keys C in the usual manner and which can be readily cut away to permit the keys to be withdrawn when it is desired to remove the plate.

E indicates blocks upon which the wear- 80 plates are usually seated.

The construction described, it will be readily seen, provides a simple, convenient, and secure means for holding the wear-plate to its seat, while at the same time permitting it to 85 be removed when required.

The structure A, with its provisions for seating and securing the said plate, may be readily cast in a single piece, although obviously the invention might be applied to a 90 structure otherwise formed.

I do not wish to limit myself to the details of construction and arrangement which I have herein shown and described, as it is obvious that the same may be varied without departing from the spirit and scope of my invention. The invention may also be used to advantage in connection with various kinds of trackwork. 95

Having thus described my invention, what 100 I claim, and desire to protect by Letters Patent, is—

1. The combination with a track or crossing member, recessed to seat a removable wear-plate, of a wear-plate seated in said recess and engaging a wall thereof both laterally and vertically, and means for maintaining said engagement.
  2. The combination with a track or crossing member, provided with a recess or pocket in its upper face, of a wear-plate seated therein and engaging a wall thereof both laterally and vertically, and keys or wedges between the said plate and the opposite wall of said recess.
  3. The combination with a track or crossing member, provided with a pocket or recess having an underbeveled wall, of a wear-plate seated in said pocket or recess and having a correspondingly-beveled face and means for securing the engagement of said wall and face.
  4. The combination with a track or crossing member, provided with a pocket or recess having an underbeveled wall, of a wear-plate seated in said pocket or recess and having a correspondingly - beveled portion engaging said wall and wedges or keys inserted between
- the opposite side of said pocket or recess and the adjacent wall of the latter.
5. The combination with a track or crossing member having a pocket therein formed with an underbeveled wall at one side and with an overhanging lip at the opposite side, of a removable wear-plate seated in said pocket and having a beveled portion engaging the said wall and at the opposite side a rib or projection, and locking devices engaging said overhanging lip and the rib or projection, substantially as described.
6. The combination with a track or crossing member having a pocket therein formed at one side with an underbeveled wall, and with a groove or channel at the base of said wall, of a wear-plate seated in said pocket and engaging the said wall, and having a rib or swell which enters the said groove or channel.

In testimony whereof I have affixed my signature in presence of two witnesses.

EDWARD OTT.
